STOP RELEASING ARM FOR THREAD
CARRIER RODSJulius Bareiss, Berkshire Heights, Pa., assignor
to Textile Machine Works, Wyomissing, Pa., a
corporation of Pennsylvania

Application September 8, 1931. Serial No. 561,544

7 Claims. (Cl. 66—129)

This invention relates to stop control means for the thread feeding guide rods of full fashioned knitting machines, and more specifically to a stop arm of the type set forth in Patent No. 1,079,915 of November 25, 1913, employed in connection with the usual end stops to additionally control rod stopping or rod releasing as required for special thread feeding movements; the object of the present improvements being to provide said 10 arm with movable rod engaging contacts particularly adapted to increase the control action of said arm for a variety of purposes.

The nature of the improvements and their manner of use will be more fully described in connection with the accompanying drawings, and the novel features thereof specifically set forth in the appended claims.

Referring to the drawings,—

Fig. 1 is a partial rear elevation of one end of 20 a full fashioned knitting machine embodying the invention.

Fig. 2 is mainly an enlarged cross sectional view taken on the line 2—2 of Fig. 1.

Fig. 3 is a plan view looking in the direction of 25 line 3—3 of Fig. 2.

Fig. 4 is a sectional view taken substantially on the line 4—4 of Fig. 3.

Fig. 1 indicates a usual end spindle 1, having a traversed stop nut 2 thereon carrying end stops 30 3 for the thread carrier rods 4, all as heretofore and operating in known manner. A pair of rod releasing arms 5 and 6 are indicated engaging in spaced slotted recesses of a nut carried support 7, said arms being jointly pivoted on a 35 fixed shaft 8, and having extensions 9 and 10 respectively engageable with a suitable cam on slur cock bar 11 adapted to partly raise said arms from their rests in said nut recesses.

The lower edges of the arms 5 and 6, within 40 said slotted recesses overlying the carrier rods 4, heretofore were straight and adapted to engage a dog 12 on any carrier rod, or such edge was cut away above certain rods and acted only on certain other rod dogs, limiting their control to a 45 single use and requiring a change of arm for varied use. One of the uses for which these arms are particularly adapted is to time the release of carrier rods used in plating, it being essential that one carrier rod have a definite lead over the 50 other, as well understood. Such control is indicated in Fig. 3, dogs 12 on the plating rods 4^a and 4^b engage the respective arms 5 and 6 to stop them as they move away from their end stops and their further movement is determined by action 55 of cam on slur cock bar 11, or a plating extension

of such bar, to sequentially lift the arms to free said rods with one leading the other at a fixed distance. Heretofore the cut away lower edge of arms 5 and 6 fixedly determined which rod would lead, and the present improvements provide 60 among other advantages for selective determination and for reverse plating when desired.

The present improvements show the rods 4 freely movable beneath the arms 5 and 6 which also clear any rod dogs except as movable contacts are lowered into the paths of the latter. Each arm 5 and 6 is shown with two movable contacts, arranged to overlie two adjacent carrier rods, and either may be separately lowered or raised as desired. And as the movable contacts are alike, description of one will suffice.

Each movable contact comprises, as shown, a stem 15 mounted for vertical movement in a bearing aperture in its respective arm, 5 or 6, one end of said stem having a contact block 16 and its opposite end an operating block 17 provided with a lateral channel 18 in which the pin 19 of a turn knob 20 engages, rotation of the latter on its pivot pin 21 acting to raise and lower contact block 16 out of and into the path of its respective 75 rod dog. Pivot pin 21 is fixed to a slide block 22 which has a limited movement on its respective arm, 5 or 6, through its slotted engagement with its securing bolt 23, such sliding movement positioning slide extension 24, either beneath block 17 80 when raised, or over said block when lowered, to lock it in adjusted position. A tension spring 25, shown as conveniently connecting two slide blocks in each arm, normally retains said slide in locking position, and sliding withdrawal of said block 17 85 when raised, or over said block when lowered, to lock it in adjusted position. A tension spring 25, shown as conveniently connecting two slide blocks in each arm, normally retains said slide in locking position, and sliding withdrawal of said block 17 90 when raised, or over said block when lowered, to lock it in adjusted position. A tension spring 25, shown as conveniently connecting two slide blocks in each arm, normally retains said slide in locking position, and sliding withdrawal of said block 17 95 when raised, or over said block when lowered, to lock it in adjusted position. A tension spring 25, shown as conveniently connecting two slide blocks in each arm, normally retains said slide in locking position, and sliding withdrawal of said block 17 100 when raised, or over said block when lowered, to lock it in adjusted position. A tension spring 25, shown as conveniently connecting two slide blocks in each arm, normally retains said slide in locking position, and sliding withdrawal of said block 17 105 when raised, or over said block when lowered, to lock it in adjusted position.

In controlling two plating carrier rods, as above referred to, the blocks 16, 16 in each arm overlie the same pair of carrier rods, and by lowering one block in arm 5 to engage one rod, and one block in arm 6 to engage the other rod, a determined lead of one rod may be accurately determined, which may be readily reversed by corresponding reversal of the lowered blocks 16, 16.

The arms 5 and 6 may be rendered idle by raising all blocks 16, or one block alone may be lowered for selavage reinforcement, the movable blocks providing for varied requirements readily effected.

From the foregoing description it is believed the 110

nature of the present improvements and their possible varied operation will be readily understood, and it will also be apparent that modifications may be readily devised within the spirit of the invention as defined in the following claims.

5 What I claim is:

10 1. In combination with a full fashioned knitting machine having thread carrier rods, a rod-releasing stop-arm having a pair of rod-releasing stops vertically mounted thereto to move into and out of rod engagement, independent moving and locking means for the respective stops, and a common tensioning means for said locking means.

15 2. In combination with a full fashioned knitting machine having thread carrier rods, a releasable rod-stop arm having a rod engaging stop movable vertically thereon into and out of rod-engaging position; and means associated with said arm for moving said stop into and out of cooperative relation with a carrier rod.

20 3. In combination with a full fashioned knitting machine having thread carrier rods, a releasable rod-stop arm having a rod engaging stop movable thereon into and out of rod-engaging position; a slide block on said arm; and means carried by said slide block for moving said stop into and out of cooperative relation with a carrier rod.

25 4. In combination with a full fashioned knitting machine having thread carrier rods, a releasable rod-stop arm having a rod engaging stop movable thereon into and out of rod-engaging position; a slide block on said arm; and locking

means carried by said slide block for retaining said stop in its adjusted position.

5. In combination with a full fashioned knitting machine having thread carrier rods, a releasable rod-stop arm having rod-engaging stops movable vertically thereon into and out of rod engaging position; slide blocks on said arm, one for each of said stops; locking means on each slide block for retaining the related stop in its adjusted position; and common means for urging said slide blocks into locking engagement with their stops.

80 6. In combination with a full fashioned knitting machine having thread carrier rods, a releasable rod-stop arm having a rod engaging stop movable thereon into and out of rod-engaging position; a slide block on said arm; locking means on said slide block for retaining said stop in its adjusted position; and means carried by said slide block and operative, on sliding thereof to release said locking means for, moving said stop into and out of cooperative relation with said carrier rod.

85 7. In a full fashioned knitting machine, thread carrier rods, a releasable rod-stop arm provided with a stop movable thereon into and out of rod-engaging position, a locking member on said stop, and locking means on said arm engageable with one portion of said member for holding said stop in operative position and with another portion of said member for holding said stop in inoperative position.
